(57) **CLAIM**

We claim the ornamental design for a multi-function anchor point for inflatable craft, as shown and described.

DESCRIPTION

FIG. 1 is perspective view of a multi-function anchor point for inflatable craft according to the present invention;

FIG. 2 is a left-end view of the anchor point, the right-end view being a mirror-image thereof;

FIG. 3 is another perspective view of the anchor point showing the generally flat bottom surface thereof;

FIG. 4 is a top view of the anchor point; and,

FIG. 5 is a front elevation of the anchor point, the rear elevation being a mirror-image thereof.
